[57] CLAIM

The ornamental design for an animal cage-mounted support, as shown.

DESCRIPTION

FIG. 1 is a front elevational view of an animal cage-mounted supported showing my new design.

FIG. 2 is a top plan view thereof.

FIG. 3 is a left side elevational view thereof.

FIG. 4 is a right side elevational view thereof.

FIG. 5 is a rear elevational view thereof.

FIG. 6 is a bottom plan view thereof.
